ENGINE PUMP JACK

William O. Bechman, Chicago, Ill., assignor to
International Harvester Company, a corpora-
tion of New Jersey

Application October 21, 1935, Serial No. 45,976

4 Claims. (Cl. 74—11)

This invention relates to a pump jack attachment for engines, and more particularly to an enclosed gear drive from the engine to the pump jack.

5 One object of the invention is to provide a pump jack and gear drive for the same which are readily attached and detached to allow for use of the engine with or without the pump jack unit.

Another object is to provide a pump jack housing that may be attached to the engine and driven from the pulley shaft of the engine without interference with the operation of the engine pulley.

15 Another object is to provide a pump jack housing construction that may be secured to a pump casing or the like to afford a solid and rigid unit between the engine and the pump casing.

20 Still another object is to provide a pump jack housing construction with a cover plate that may be readily removed without disturbing the connection between the housing and the engine.

25 Still another object is to provide a pump jack housing construction that will afford an oil-tight seal between the pulley and the housing cover plate and the pulley shaft.

Other objects will be apparent from the following description and drawings, in which:

Figure 1 is a side elevational view embodying the invention and showing the pump jack in place on the engine; and,

Figure 2 is a plan view of the same partly in section, the sectional portion being viewed substantially along the line 2—2 on Figure 1, and looking in the direction of the arrows.

35 The reference character 10 denotes an internal combustion engine of the stationary or utility type. The drawings illustrate only that portion of the engine which is necessary to describe and disclose the invention.

40 The crank-case 11 and the cylinder block 12 are cast in one piece, as is customary in the construction of one cylinder engines, and have formed integral therewith supporting lugs or ears 13, which with securing bolts 14 secure the engine 10 to a pair of base rails 15 and 15'. These rails are preferably formed of channel steel and are provided with rounded ends and lifting hand grips 16.

45 A crank-shaft 17, indicated in dotted lines in Figure 1, extends transversely across the crank-case 11 and carries at one end the usual fly wheel 18. Above the crank-shaft 17 and parallel to the crank-shaft is the pulley shaft 19, which is formed as an extension of the cam shaft 20.

50 The cam shaft 20 is gear driven from the crank-shaft, as is customary in the construction of internal combustion engines.

Secured by bolts 21' to the pulley side of the engine over the opening through which extends

5 19, is the pump jack gear housing 21. This housing extends rearwardly from the engine and is provided at one side with an integral bearing housing 22, which is provided with a bracket 23 and U-bolts 24. The bracket 23 and U-bolts 24 provide a rigid support for attachment to a pump casing 25 indicated in both figures in dotted lines, thus affording a solid and compact unit between the engine 10, through the housing 21, and the pump casing 25, reducing vibration therebetween to a minimum.

10 The housing 21, at the pulley side of the engine, is supported by an integral leg 26 secured by a bolt 27 to the turned-over edge of the channel steel base rail 15 near the lifting hand grip 16.

15 A support 28, preferably formed as a stiff strap forging, is bolted to the engine 10 at its rearward end, and extends rearwardly to the bearing housing 22 of the gear housing 21, where it is secured to the underside of the bracket 23 by 20 a bolt 29. The support 28 is further bent downward, as at 30, toward a cross support 31, which is bolted at its opposite ends to the base rails 15 and 15'. The bent extension 30 of the support 28 is secured to this cross support 31 by the bolt 25 32. This construction provides for support at both sides of the rearward end of the pump jack housing 21 and for continuous rigidity and compactness of the entire unit.

20 It will be apparent from the foregoing description that the pump jack housing may be easily and readily detached from the engine to allow the engine to be used for other purposes.

25 Extending through the housing 21 and carried at one end in the bearing housing 22 is a transverse shaft 33, at opposite ends of which and outside of the housings 21 and 22, are mounted crank-wheels 34. These crank-wheels are identical in construction and are held fast to each end of the shaft 33 by split hubs 35, clamp bolts 36, and driving keys 37. A cover plate 38 covers the housing 21 and forms an additional bearing for the shaft 33, as at 39. Within the housing 21 and enclosed by the cover plate 38, the shaft 33 has keyed and clamped thereto a gear 40.

30 Intermediate the shaft 33 and the pulley shaft 19 and within the housing 21 and enclosed by the cover plate, is a short transverse stub shaft 41. Mounted for rotation on the stub shaft 41 is a 35 pinion 42 and an integral gear 43. The pinion 42 meshes with and engages the gear 40 on the shaft 33.

35 Mounted on the pulley shaft 19 adjacent and outside of the engine, and enclosed by the gear 50 housing 21 and cover plate 38, is a driving pinion 44, which extends substantially the length of the pulley shaft 19 and which is keyed thereto by a driving key 45. The pinion 44 is adapted to mesh with and drive the gear 43 on the shaft 60

41, which also carries integrally with the gear 43 the pinion 42, which in turn meshes with and drives the gear 40 on the shaft 33. A continuous, enclosed gear drive is thereby provided between the engine 10 and the crank-wheels 34.

The pinion 44, beyond its toothed portion, is provided with a series of annular grooves 45 for a purpose to appear later. Adjacent the outer end of the pinion 44 and mounted over the outer end of the pulley shaft 19, is the customary drive pulley 46. This pulley 46 is provided with a hub portion 47 and annular recesses 48 and 48' on either side of the hub portion 47. Bolts 49, extending through the hub portion 47 and into the pinion 44, secure the pulleys 46 to the pinion and establish a driving connection therewith.

The portion of the cover plate 38 of the pump jack housing 21 surrounding and enclosing the pulley shaft 19 and driving pinion 44 is formed as a substantially annular hub extension 50, which encircles the outer end of the pinion 44 about the annular grooves 45, and substantially abuts the hub portion 47 of the pulley 46. An annular groove 51 within the hub extension 50 of the cover plate 38 cooperates with the outermost annular groove 45 on the pinion 44 to form an annular recess for retaining the circular lubrication seal 52. The other grooves 45 are provided as oil carrying grooves, as is well known to those skilled in the art.

From this description it will be apparent that the pulley 46 is still available for use while the pump jack housing and unit are in place and in operation. It will be further apparent that the pulley 46 may be removed from the pinion 44 by the removal of the bolts 49 without disturbing the housing 21 or the cover plate 38. A small cap (not shown) may be secured over the opening left by the removal of the pulley in the hub extension 50 of the cover plate 38, to maintain the lubrication seal and to facilitate operation of the engine and pump jack without the pulley.

In order to effect a connection between the pump jack and the pump, the crank-wheels 34 are provided with holes 53 arranged on radial spokes of the wheels. These holes 53 are spaced for adjustment and are adapted to receive pitman pins 54. Pitmans 55 for driving the pump are secured at one end by these pitman pins 53 to the crank-wheels 34 and at the opposite ends, to the pump, not shown, as is well understood by those skilled in the art.

It will now be apparent that an enclosed gear drive is provided between the pulley shaft 19 and the crank-wheel shaft 33. The shaft 20, which is in effect the cam shaft of the engine, is gear driven by the crank-shaft 17 through the customary gears, not shown.

It is often necessary or desirable to operate the engine without the pump jack attached. To accomplish this, the bolts 49 are removed and the pulley 46 detached from the pinion 44, and the pinion removed from the shaft 19. Next, the U-bolts 24 are removed from the pump casting 25, and the bolt 29 removed from the support 28 and the bracket 23. The bolts 21' are removed from the housing 21 and the engine 10, and the housing 21 together with the cover plate 38, the crank-wheels 34 and shaft 33, the enclosed gears 40 and 43, and the pinion 42, may be removed as a unit.

It is the intention to cover all modifications of the above described invention which do not in

material respects depart from the spirit and scope of the appended claims.

What is claimed is:

1. In a combined pump jack and internal combustion engine, the combination of a shaft extending from and driven by said engine, a pinion mounted on said shaft for rotation therewith outside of the engine, a pulley mounted concentric with the shaft and secured to the pinion for rotation therewith, a gear housing mounted on one side of the engine concentric with the shaft to enclose the pinion and to form a lubrication seal with the pulley, said gear housing extending rearwardly beyond the engine, a support between the engine and the housing at its rearward end, a gear mounted for rotation on a second shaft within the gear housing and adapted to be driven by the pinion, a second pinion formed integral with said gear, a third shaft extending through the gear housing, crank-wheels at opposite ends of said third shaft outside of the gear housing, a second gear mounted within the gear housing on said third shaft for rotation therewith and adapted to be driven by the second pinion within the gear housing to form a continuous gear drive from the engine to the crank-wheels. 5 10 15

2. In a combined pump jack and internal combustion engine, the combination of a shaft extending from and driven by said engine, a pinion mounted on said shaft for rotation therewith, a gear housing mounted at one side of and extending beyond the engine, an annular portion formed on said housing and surrounding the pinion and the shaft, a bearing housing on the gear housing extending transversely at one side of the engine, a support between the bearing housing and the engine, a shaft carried in said bearing housing and gear housing, and drive gearing within the gear housing for driving said shaft from the pinion. 30 35 40

3. In a combined pump jack and internal combustion engine, the combination of a shaft extending from and driven by said engine, a pinion mounted on said shaft for rotation therewith, a pulley mounted on said shaft for rotation therewith, a gear housing mounted at one side of and extending beyond the engine, said gear housing having an annular portion thereon surrounding the pinion and the shaft and forming with the pulley a lubrication seal therebetween, a crank shaft mounted in the gear housing in the portion beyond the engine, crank-wheels mounted for rotation with the crank-shaft, and drive gearing within the housing for driving said crank-wheels from the pinion. 45 50 55

4. In a combined pump jack and internal combustion engine, the combination of a shaft extending from and driven by the housing, a pinion mounted on said shaft for rotation therewith, said pinion being formed with an annular reduced end portion, a pulley mounted on said shaft and secured to the pinion for rotation therewith, said pulley having a flat faced hub portion, a gear housing mounted on the engine between the engine and the pulley, an annular portion on said gear housing surrounding the pinion adjacent the pulley, said annular portion being provided with an internal annular recess surrounding the reduced end portion of the pinion, and a lubrication seal between said annular recess and the reduced end portion of the pinion and cooperating with the flat hub of the pulley. 60 65 70 75
